UNITED STATES PATENT OFFICE.

JOHN WILLIAMS, OF WASHINGTON, DISTRICT OF COLUMBIA.

SHOW CASE.

Application filed February 23, 1926. Serial No. 90,052.

My invention relates to a show case particularly designed to display baked products. It is an object of my invention to produce a show case which will display in a suitable manner, the baked products which it is designed to contain but which is simple in construction, attractive in appearance, and at the same time maintains the products in such a manner that they are readily accessible to the clerk.

It is a further object of my invention to produce a case providing separate compartments each of which is normally closed so as to prevent the access of dust and dirt to the contents of the case.

Further objects of the invention will appear as the description proceeds with reference to the drawings in which:

Figure 1 is a perspective view of my improved show case.

Figure 2 is a rear elevation with two of the covers shown in raised position.

Figure 3 is a vertical cross section taken on the plane indicated by the line *a—a* in Figure 2.

Similar reference characters refer to similar parts throughout the several figures.

My show case comprises a frame consisting of vertical angled uprights 1 connected by longitudinally extended members 2 and transverse members 3. The transverse members 3 are inclined as clearly shown on Figures 1 and 3 of the drawings. Said longitudinal members are spaced apart, vertically, a sufficient distance to permit a clear view of the contents of the sections of the case from the front and to permit ready access to said contents from the rear.

Secured to the longitudinal and transverse members are supporting shoulders 4, serving to support sheets of veneer 5 forming the bottom of the receptacle of the case. As a cover for each receptacle, I provide a frame consisting of longitudinal members 6 and 7 and cross members 8, 9, 10, and 11 between which are arranged panes of glass 12, as is clearly shown on the drawings. These frames are notched as shown at 13, to fit in the angled uprights 1. Said frames are unsecured to the frame of the case but are designed to completely cover the receptacle formed as above described. By this arrangement the covers may be raised to dispense the products contained therein or to renew the supply.

Handles 14 are provided on the rear of

each cover to facilitate the raising of the cover. In order that the cover may be retained in a raised position when necessary to remove some of the contents of the case or for any other reasons, I provide latches 15 that engage the handles of the covers when the latter are tilted as shown in Figure 2. These latches are arranged with one arm in the path of the handles and are swung about their pivots to automatically engage said handles when the covers reach their tilted position. The latches may be released and the covers replaced by manipulating the catch 16 as will be readily understood.

Preferably the top cover is held in open position by a supporting member 17, that is pivotally secured to a bracket 18 fastened to the underside of the top cover. The arrangement is such that when this cover is raised, support 17 will assume an upright position. This cover may be closed by slightly raising the cover and manually swinging the support 17 out of engagement with the bottom of the top receptacle.

In the operation of my improved show case, the case is put in position spaced from the wall of the store room. Preferably though not necessarily the case is made of a length which is a multiple of the width of the pans customarily used in bakeries, and of a width substantially conforming to the length of said pans, so that the pans containing the baked products may be placed in the receptacles without waste of space, if this practice is deemed desirable. The pans may be inserted in the case by simply tilting the covers until they are automatically held in their elevated position. The pans may then be readily inserted. In the same way the products of the case may be dispensed. The automatic means for retaining the covers in elevated position permits full use of both hands of the clerk in removing and adding to the contents of the case. It will be observed that, by the arrangement shown, the contents of each receptacle is maintained separately encased from the contents of every other receptacle and that all the receptacles are so arranged that they properly display their contents and fully protect them from dust and dirt.

While I have above described in detail the preferred form of my invention, it should be understood that my invention is not limited to the precise details but that the scope of

my invention is to be determined from the following claims.

Claims:

1. A counter show case of the type that is inaccessible from the front thereof and accessible from the rear, comprising a plurality of fixed forwardly inclined receptacles arranged in spaced relation to each other, a transparent, removable and tilttable cover for each receptacle, said covers being arranged to be tilted from the rear of the case, and means to automatically engage the several covers when they are swung to raised position, whereby ready access to the several receptacles may be had.
2. A counter show case of the type in which the contents are inaccessible from the front of the case but accessible from the rear thereof, comprising a plurality of spaced forwardly inclined receptacles, transparent covers for said receptacle, each cover being tilttable about an axis located in the front of the case, and means to hold said covers in such tilted position, the arrangement being such that containers may be readily slid beneath said covers and down such inclined receptacles into position in the case.

3. A show case comprising a plurality of spaced, inclined, receptacles, a removable and tilttable cover for each receptacle, a handle for each cover secured to the edge thereof and spring latches attached to the overlying receptacles to automatically engage said handles when the covers are tilted.

4. A sanitary show case of the counter type designed to be inaccessible from the front and accessible from the rear, comprising uprights, a forwardly inclined receptacle, provided with a transparent tilttable cover designed to swing about an axis at the front of the case, secured to said uprights and constituting the top of the case; a plurality of forwardly inclined receptacles secured to said uprights and arranged beneath and spaced from said first named receptacle; said last named receptacles being provided with transparent covers designed to swing about axes at the front of the case; and means to automatically hold said covers including the top cover in elevated position when the covers are raised.

JOHN WILLIAMS.
